UNITED STATES PATENT OFFICE.

JOSEPH FRANCIS O'BYRNE, OF FREEPORT, NEW YORK.

HOOD.

1,333,214.

Specification of Letters Patent.

Patented Mar. 9, 1920.

Application filed November 12, 1917. Serial No. 201,433.

To all whom it may concern:

Be it known that I, JOSEPH FRANCIS O'BYRNE, a citizen of the United States, and a resident of Freeport, in the county of 5 Nassau and State of New York, have invented certain new and useful Improvements in Hoods, of which the following is a specification.

This invention relates to improvements 10 in hoods for automobiles and like vehicles.

The invention also relates to improved finishing covers for such hoods, which covers are decorated by the method disclosed in my co-pending applications, Serial No. 148,193, 15 filed February 12, 1917, and Serial No. 174,139, filed June 11, 1917.

An object of the invention is to provide an improved hood to inclose the space between the dash and radiator of an automobile, which hood consists of a one-piece flexible developable member, adapted to bend about and fit the dash and radiator, and when so positioned to inclose the space therebetween, together with means whereby 25 the member may be held in closed position or may be moved to other positions to expose said space from either side of the automobile.

Another object of the invention is to provide in combination with a hood of the character described an improved protecting and decorative covering therefor.

Other objects and advantages will appear in the following description and will be particularly pointed out in the appended claims.

The invention, in an embodiment at present preferred, is disclosed for illustrative purposes in the accompanying drawings, in which—

40 Figure 1 is a perspective view illustrative of the improved hood construction;

Fig. 2 is a view similar to Fig. 1 showing the hood in closed position;

Fig. 3 is a sectional view illustrative of 45 the manner of building up the hood covering with decorative and protective layers;

Fig. 4 is a similar view illustrative of the manner of holding the assembled layers of the hood together; and

50 Figs. 5 and 6 are fragmentary sectional views showing modifications in the arrangement of decorative and protective layers.

According to one feature of the invention, the hood is made up from a single one-piece 55 developable member 10 of flexible material. There are no joints, hinge connections and

the like, but, on the contrary, member 10 is simply and inexpensively produced by cutting from suitable material, as thin sheet metal, a piece of such shape that it may thereafter be curved to fit about the dash *d* and radiator *r*. That is, the surface of the hood, when in position to inclose the space between the dash and radiator, is a developable one and can be rolled out into a flat sheet. Conversely, the hood is such that it may be made up by simply cutting out its developed shape from a flat sheet and then curving it into position to inclose the hood and radiator. The hood therefore is properly termed developable since it may be developed into a flat sheet. The dash and radiator have flanges 11 and 12, respectively, which are directed toward one another and which provide supporting surfaces for two 70 edges of the member 10. The exterior surfaces of flanges 11 and 12 are readily developable, whereby the member 10 may be cut from a single flat piece of material and thereafter curved into shape to fit around flanges 11 and 12 and between the dash and radiator *r* for the purpose of inclosing the space therebetween.

The member 10 is of flexible, readily bendable material, which does not of itself 85 retain curvatures but tends to resume its original flat form.

It is made of such material that it may be bent back and forth many times without cracking or being otherwise injured. The member 10, therefore, requires 90 means to retain it in position about the dash *d*, radiator *r*, and flanges 11 and 12. Such means are provided in the shape of strips 13 secured to the outer face of the dash near the lower ends thereof, and similar strips 14 95

on the radiator *r*. Strips 13 and 14 are substantially U-shaped in cross-section and afford slots in which the member 10 may be positioned, as shown in Fig. 2, and effectively held against longitudinal displacement.

The member 10 is thus engaged along two edges and at four corners by the parts 13 and 14. The other two edges of member 10 preferably have the customary bead *b* (Fig. 2), and on a frame *f* which 100

supports the dash *d* and radiator *r*, are mounted retaining clips *c*, of the usual well-known form, which engage with bead *b* and hold the member 10 tightly stretched around the flanges 11 and 12. Thus, the hood 10 is 105

effectively held by simple means against displacement in all directions.

Preferably, handles *h* are provided on hood 10 and openings *o* are formed in the latter, all as shown in Fig. 2, for the usual reasons.

5 Means are also provided, whereby the hood 10 may be held in other positions for the purpose of exposing the space between the dash and radiator from either side of the automobile. Such means consists of vertically-arranged U-shaped strips 15 on the dash *d* and like strips 16 on radiator *r*. The hood 10, instead of being positioned in both strips 13 and both strips 14, as in Fig. 2, may be positioned on one side by one strip 13 and 10 one strip 14 and on the other side by one strip 15 and the opposite strip 16, all as clearly indicated in Fig. 1. Thus, the space between members *d* and *r* will be completely exposed on one side and may be exposed on 15 the other side by positioning the hood 10 in those strips 13, 14, 15 and 16 which are shown as unoccupied in Fig. 1.

It is to be noted that the hood 10 may be entirely removed with convenience whenever desired and may be opened and closed as readily as the prevalent type of hood. The hood, thus, retains all the advantages of the usual hood and in addition is advantageous on account of its simple and inexpensive construction. A further and most desirable advantage incident to the construction of the hood as described, lies in the fact that when positioned as in Fig. 2 it presents a remarkably improved appearance 30 over hoods of the ordinary types, since it presents a single smooth and unbroken surface which results in a distinctly pleasing effect.

According to another feature of the invention, the hood is made as herein disclosed for the effective application of decorative and protective material. The hood, instead of being a single sheet, as described, may consist of a plurality of superposed sheets, 40 as shown in Figs. 3 to 6, inclusive. Considering Fig. 3, the hood covering may be made up of a sheet 10' of similar material and in a similar manner as member 10 described, except that it is preferably somewhat larger 45 in order to afford a milled edge 17 along each of its four edges. Upon this member 10' is laid a sheet of transparent material 18 to which paint, varnish or other coloring material has been previously applied in a layer 19. The four milled edges 17 are then rolled up as indicated in Fig. 4, to bring the milled edges against the top edges of the transparent material 18. Pressure is then applied to force the overlapping and milled 50 portions of member 10' against the layer 18 to compress and bind it along its four edges. Preferably, the several layers are dished slightly, as indicated in Fig. 3, so that the sheet 10', when subsequently flattened out 55 will stretch the transparent material into

a smooth flat sheet, the grip of the milled portions 17 being sufficient to securely hold the sheet 18 under tension. In the drawings, the several component layers of the hood covering have been shown in exaggerated form for clearness, but in reality they are made very thin so that the entire assembly is readily flexible.

70 The transparent sheet 18 may be of any suitable material which is transparent, flexible, and preferably highly polished. Celuloid is an example of a material which has the requisite qualities, but, owing to its inflammability, is not generally satisfactory. There are other materials, however, closely resembling celluloid in appearance, but not inflammable, which are suitable, such as cellulose acetate material, and that material now largely used for motion picture films, for example. Such materials as described 75 are furthermore advantageous in that they are waterproof.

The decorative layer 19 is of suitable coloring matter, preferably paint, varnish, or the like. When paint and the like is employed for the decorative layer 19, it need not be applied with particular care to the transparent sheet 18. It may be applied in a rough way if desired by dipping the sheet in paint or spraying or pouring the paint 80 on the sheet. The irregularities in the outer surface of the decorative layer do not matter, for, despite these irregularities, the inner surface is necessarily smooth since it is contiguous to the polished transparent sheet 18. 85 Thus, the decorative layer 19, when viewed through the transparent material 18, is of absolutely uniform color and possesses a high degree of luster, as more fully pointed out in the above-named co-pending application, and this luster is not obtainable in any other manner, so far as I am aware, as conveniently and efficiently as that herein described.

100 The covering made up as described may be applied to and between radiator *r* and dash *d* in the same manner as the single sheet hood 10, already described.

The compound hood covering just described may be made up of other combinations of layers. Thus, as shown in Fig. 5, the sheet 10' may be painted, varnished and rubbed down to form a polished decorative layer 20. The latter is then covered and protected against injury by a layer 21, which 115 may consist of felt or like suitable material. The transparent sheet 18 having a decorative layer 19 on one face, is then applied to the layer 21 with the layer 19 adjacent the latter. The decorative layer 19 will then 120 be seen as in the covering shown in Fig. 3, but when, for any reason, a new finish, or a finish of different color, is desired, the layers 18, 19 and 21 may be readily removed to expose a fresh and lustrous layer 20, hitherto 125 130

concealed by layer 21. Another desirable modification consists in applying to the unfinished member 10', the transparent layer 18, which has a decorative layer 22 on its outer face, as well as the layer 19, applied as heretofore described. The layer 22 is applied in the usual manner and rubbed down and polished. When layer 22 becomes worn or loses its luster, it may be readily removed, as with paint remover, to reveal the fresh, highly polished, lustrous, decorative layer 19. Obviously, a layer similar to the layer 22 shown in Fig. 6 may be applied to the outer surface of the layer 18 in the modification which is shown in Fig. 5, and many other modifications will readily occur to those skilled in the art.

The compound coverings described are particularly advantageous in that the decorative material 19 may be economically applied, and even in a very rough manner, to produce highly polished decorative surfaces having an improved luster which can only be otherwise approximated by careful and expert work and at considerable expense due to the repeated "rubbing down" processes involved. Moreover, the decorated surfaces are effectively protected against the constant bombardment by minute articles of sand, dirt, and the like, so that the highly lustrous surfaces may be retained for long periods. Furthermore, the polished decorated surfaces of automobiles undergo repeated washings, and thus repeated scratching, but with the covering described, the paint or the like is not affected, since the washing comes on the transparent material alone. Any dulling of the latter, caused by repeated washing, scratching or oxidation may be readily removed by buffing the sheet, without touching the inner painted surface thereof.

The invention has been described in a preferred form with detailed variations for the purposes of illustration, but the scope of the invention is defined by the appended claims rather than by the foregoing description.

What I claim is:—

1. The combination with the dash and radiator of an automobile of a hood, said hood comprising a single developable sheet of material adapted to be moved into position to fit about the dash and radiator to inclose the space therebetween, and to be moved to another position to expose the space therebetween, and means to hold the hood in either of said positions.

2. A hood for an automobile, comprising, a one-piece flexible member adapted to fit about the dash and radiator of an automobile to inclose the space therebetween, means to releasably hold the hood when thus positioned, said hood being bendable into other positions to expose said space and entirely removable if desired when said means are released.

3. A hood for an automobile, comprising, a one-piece flexible developable member shaped to fit about the dash and radiator of an automobile, and adapted when thus positioned to inclose the space therebetween, means to removably hold the hood when thus positioned, other holding means adjacent the first-named means, each thereof adapted to receive the far side of the hood while the near side is held by the first-named means, whereby the hood may be moved to expose said space from either side of the automobile.

4. An automobile hood, comprising, a flexible member shaped to fit about the radiator and dash of an automobile to inclose the space therebetween, a flexible transparent layer on said member, a layer of coloring material between the member and said transparent material, and means to removably hold the hood in position to inclose said space.

5. The combination with the dash and radiator of an automobile, of a hood to inclose the space therebetween, said hood comprising a sheet of flexible material, a sheet of flexible transparent material outside the first-named sheet, a coloring layer covering the inner surface of said transparent material, and means to hold said sheets together, the hood being adapted to be bent to fit the dash and radiator, and means to hold the hood when thus positioned.

6. An automobile hood, consisting of a finished flexible member, a transparent layer covering the finished surface of said member and a coloring layer covering the inner surface of said transparent layer, means to hold the latter to said member, said member being shaped to fit about the dash and radiator of an automobile to inclose the space therebetween, and means to removably hold the hood in closed position.

7. An automobile hood, consisting of a finished flexible member, a transparent layer covering the finished surface of said member and a coloring layer covering both surfaces of said transparent layer, means to hold the latter to said member, said member being shaped to fit about the dash and radiator of an automobile to inclose the space therebetween, and means to removably hold the hood in closed position.

8. An automobile hood, consisting of a flexible member, a transparent layer covering the outer surface of said member and a coloring layer covering the inner surface of said transparent layer, means to hold the latter to said member, said member being shaped to fit about the dash and radiator of an automobile to inclose the space therebetween, and means to removably hold the hood in closed position.
